UNITED STATES PATENT OFFICE.

JOSEPH E. FLANIGAN AND FRANCIS E. ASHTON, OF CHESTER, PENNSYLVANIA, AS-SIGNORS TO CROMPTON & KNOWLES LOOM WORKS, OF WORCESTER, MASSACHUSETTS, A CORPORATION OF MASSACHUSETTS.

MULTIPLE-PLUNGER WEFT DETECTOR.

Application filed June 4, 1923. Serial No. 643,211.

To all whom it may concern:

Be it known that we, JOSEPH E. FLANIGAN and FRANCIS E. ASHTON, both citizens of the United States, both residing at Chester, in the county of Delaware and State of Pennsylvania, have invented a new and useful Multiple-Plunger Weft Detector, of which the following is a specification.

This invention relates to a weft detector 10 of the general type shown in the prior patent to E. H. Ryon, No. 1,221,768, dated April 3, 1917.

It is the general object of our invention to improve the construction therein shown by 15 providing novel and useful devices for holding the plungers in operative or rearward position and for permitting separate yielding forward movement of each plunger as it is engaged by a sufficient supply of weft or 20 the active weft carrier.

To the attainment of this object, we provide a separate swinging weight for each plunger, movable outward or forward from its center when the corresponding plunger is 25 moved forward. We also provide a novel device for simultaneously withdrawing all of the weights and plungers upon the occurrence of weft carrier transfer.

A preferred form of our invention is 30 shown in the drawings in which—

Fig. 1 is a side elevation of parts of a loom embodying our improvements, with the lay and shuttle shown in section;

Fig. 2 is a front elevation of the parts 35 shown in Fig. 1;

Fig. 3 is an enlarged plan view of our invention;

Fig. 4 is an enlarged side elevation of the parts shown in Fig. 3;

Fig. 5 is a side elevation of one of the 40 swinging weights;

Fig. 6 is a partial plan view of one of the weights, looking in the direction of the arrows 6 in Fig. 5; and

Fig. 7 is a perspective view of the means 45 for withdrawing the plungers upon transfer.

Referring to Figs. 1 and 2, we have indicated a portion of a loom frame 10, a magazine frame 11, a transerrer 12, a lay 50 13, a shuttle box 14, a binder 15 and a shuttle 16 in which is mounted a bobbin or weft carrier 17. The bobbin has a plurality of holes 18 distributed in different angular relations along the length of the barrel there-

of and positioned for alignment with some 55 one of the plungers 20 of the weft detector.

These plungers are mounted to slide in a stand or frame 21 (Fig. 4) which is yieldingly held in position against a fixed bracket 22 (Fig. 1) by a bolt 23 and spring 24. 60 The plungers 20 are of a general U-shape with a short upper portion 25 normally positioned in the path of a floating lever 26 (Fig. 2).

This lever 26 normally swings about a 65 pivot 27 at the lower end of a link 28 connected to the mechanism of the weft carrier magazine.

An actuator 30 is vertically reciprocated in a fixed bearing 31 and at its upper end is 70 pivoted at 32 to the floating lever 26. When the portions 25 of the detectors 20 are all moved out of the path of the lever 26 by engagement with a full bobbin or weft carrier, the lever 26 swings about its pivot 27 75 on the link 28. If, however, the end of the lever 26 engages one of the plunger portions 25 on the downward stroke of the lever, it thereafter swings about the detector as a pivot, drawing the link 28 downward and 80 releasing a selected weft carrier for subsequent transfer.

The mechanism thus far described is in general of the usual type and in itself forms 85 no part of our invention, which relates particularly to the provision of a plurality of swinging weights 35 pivoted upon a stud 36, mounted in an upward projection of the stand 21. Each weight 35 has a grooved rear face, as indicated at 37 in Fig. 6, and engages the upright portion of one of the detectors or plungers 20. Each weight also 90 has a forwardly offset portion 38 which increases its effective pressure upon the associated plunger.

The weights swing freely about the stud 36 and yieldingly hold the plungers 20 in the position indicated in Figs. 3 and 4 of the drawings. Whenever a plunger is engaged by weft on the weft carrier and is forced 100 forward, the associated weight swings freely outward or forward, permitting yielding movement of the plunger, and immediately returns the plunger to normal or operative position when the pressure of the weft carrier thereon is removed. Each plunger is thereby held yieldingly in operative position, independently of the other plungers, 105

and movement of one plunger from such position does not remove the yielding pressure from the other plungers, as was the case in the Ryon patent above cited.

5 Special provision is also made for withdrawing all of the plungers when a weft carrier is to be transferred and for this purpose I provide the releasing device shown particularly in Fig. 3. This device consists
10 of a frame 40, having open notched portions 41 adapted to bear upon the stud 36, and embracing the series of weights 35.

An arm 42 extends behind the upright portions of the plungers 20 and a lug 43 is
15 positioned for engagement by a stud 44 (Fig. 2) movable with the transerrer 12 and swinging the frame 40 forward as the transerrer descends. Upon such movement, the arm 42 engages and withdraws all of the
20 plungers 20 from the path of the incoming weft carrier.

Having thus described our invention and the advantages thereof, we do not wish to be limited to the details herein disclosed otherwise than as set forth in the claims, but what we claim is:—

1. In a loom, a weft detector comprising a stand, a plurality of detecting plungers mounted for independent movement in said stand, a horizontal stud fixed in said stand above said plungers, and a plurality of separate segmental weights pivotally mounted for independent forward and upward movement against gravity and each yieldingly engaging one of said plungers to normally maintain said plunger in rearward operative position, said weights being mounted in closely parallel relation and each weight being of an extreme thickness substantially equal to the distance between the centers of adjacent detecting plungers.

2. In a loom, a weft detector comprising a stand, a plurality of detecting plungers mounted for independent movement in said stand, a plurality of separate weights mounted for independent swinging movement and each yieldingly engaging one of said plungers to normally maintain said plunger in rearward operative position, and means to
50 simultaneously withdrawn all of said plung-

ers and weights from normal operative position.

3. In a loom, a weft detector comprising a stand, a plurality of detecting plungers mounted for independent movement in said stand, a plurality of separate weights mounted for independent swinging movement and each yieldingly engaging one of said plungers to normally maintain said plunger in rearward operative position, and means to withdraw all of said plungers and weights, said means comprising a frame embracing said weights and having an arm positioned behind a portion of each plunger.

4. In a loom, a weft detector comprising a stand, a plurality of detecting plungers mounted for independent sliding movement in said stand, a plurality of separate swinging weights each yieldingly engaging one of said plungers, a fixed stud on which said weights are pivoted, and means to withdraw all of said plungers, said means comprising a frame embracing said weights and pivoted on said stud and having an arm positioned behind an upright portion of each plunger.

5. In a loom, a weft detector comprising a stand, a plurality of detecting plungers mounted for independent sliding movement in said stand, a plurality of separate swinging weights each yieldingly engaging one of said plungers, a stud on which said weights are pivoted, and means to withdraw all of said plungers, said means comprising a frame embracing said weights and having open bearing notches fitting said stud and an arm positioned behind a portion of each plunger.

6. As an article of manufacture a segmental weight for a multiple plunger weft detector, said weight having a recessed end portion adapted to receive the forward end of a weft detecting plunger and having a portion substantially equal in thickness to the distance between the centers of adjacent plungers, and having a forwardly projecting counterweight portion.

In testimony whereof we have hereunto affixed our signatures.

JOSEPH E. FLANIGAN.
FRANCIS E. ASHTON.
